Specification for Design.

Patented July 6, 1920.

Application filed October 2, 1919. Serial No. 328,067. Term of patent 14 years.

To all whom it may concern:

Be it known that I, ANSEL C. HULBERT, a citizen of the United States, and resident of the city and county of San Francisco, State of California, have invented a new, original, and ornamental Design for a Switch-Casing, of which the following is a specification, reference being had to the accompanying drawing, forming a part hereof.

In the drawing:

Figure 1 is a front elevation of the switch casing, and

Fig. 2 is a side elevation.

Fig. 3 is a plan view of the switch.

What I claim is:

The ornamental design for a switch casing substantially as shown.

In testimony whereof I have hereunto set my hand this 27th day of September, 1919, in the presence of the two subscribed witnesses.

ANSEL C. HULBERT.
